UTILITY DEVICE

Filed Feb. 10, 1930

UNITED STATES PATENT OFFICE

ERNEST BERNITZ, JR., OF LA MESA, CALIFORNIA

UTILITY DEVICE

Application filed February 10, 1930. Serial No. 427,404.

My invention relates to utility devices and particularly to such devices the use of which are associated with the re-conditioning of motor or cylinder heads and the like, a particular object being in providing a convenient means for supporting in an adjustable manner cylinder heads during the process of grinding valves, reconditioning valve seats and removing valve springs and pins.

10 It is purposely intended for use with shop equipment in automobile repairing. In some instances where the rocker arm is not removed from the cylinder head a special auxiliary attachment is used. While not being used the 15 attachment is advanced to a forward position so as not to interfere with the operation of the remaining equipment.

In the accompanying drawings:

Fig. 1 is a perspective view of the entire 20 assembly of the different parts constituting the invention illustrating a detachable cylinder head in place.

Fig. 2 is a sectional view taken transversely thru the cylinder head illustrating the manner 25 in which a valve pin is removed, and also shows one of the individual bolsters underneath the valve disk to support the valve body after the valve pin has been removed from the valve.

30 Fig. 3 is a perspective view of the invention; somewhat similar to Fig. 1, but with this difference however, the cylinder head is folded over. This position permits the removal of the valve bodies. The compression tool in this view is shown placed in the inoperative position.

Fig. 4 is a perspective view of a ledge which 40 extends athwart the frame and is placed directly beneath the cylinder head adapting it for carrying the individual slideable bolsters.

Fig. 5 is a plan view of a bolster.

Fig. 6 is a view taken on line 6-6 of Figure 4.

45 Fig. 7 is a perspective view of one of the supporting members for a detachable cylinder head and the vertically adjustable plate to regulate the height of the ledge shown in Fig. 4.

50 Fig. 8 is a transverse section on the line 8-8 of Fig. 7.

Fig. 9 is a perspective view of the compressor tool.

Fig. 10 is a transverse section on the line 10-10 of Figure 9.

Fig. 11 is a perspective view of one of the 55 attaching links.

Fig. 12 is a perspective view showing an alternate construction of the adjustable compressor tool fulcrum.

Referring in detail to the drawings, the 60 invention comprises a main supporting frame composed of a base plate 1 containing screw or bolts holes 4, and two end frames 2, which are of like construction, adjustable thereupon. Said end frames 2 contain a slotted hole 3 at one end through which is shown extended an inter-connecting rod 5 running athwart the frame. Said inter-connecting rod 5 is adjustable within the slotted holes 3 and has an anchor rod nut 6 on the inside of the end frames, and an anchor rod wing nut 7 on the outside of the end frames for rigidly holding the aforementioned inter-connecting rod in position, as well as bracing the end frames 2.

75 There is similarly located, and adjustable as to width, a second rod 8 inter-connecting the end frame 2. It likewise has an anchor nut 9 bearing on the inside of the end frames and an anchor wing nut 10 bearing on the outside of the end frames, and serving a purpose similar to that of the anchor rod 5.

To the anchor rod 8 is rotatively fastened a pair of straps 11 containing slotted holes 14 and a loop hole 15. Said straps, in turn, being adapted to be fastened to a detachable motor head 16 by means of a bolt 12 and a wing nut 13. The straps 11 are shown in Fig. 11.

90 There are two distinct positions of the motor head shown in the drawings, one in Fig. 1 when the component parts are assembled, another in Fig. 3 where they are disassembled. In Fig. 1 is noted means for dismantling the 95 motor head, preliminary to re-conditioning it, while in Fig. 3 the component parts are removed as they will be to enable a mechanic better to perform his work. In this view the motor head is also shown placed in a position 100

that will properly afford access for performing the re-conditioning work.

The loops 15 permit the straps 11 to slide upon the rods 8 whereby they may be made to accommodate the various sized motor heads.

There is similarly attached to the rod 8 a pair of supporting beams 21, which are adapted to carry the weight of the motor head. Said attaching means consists of an eye loop 21a through which is projected the rod 8, the free ends of the beams 21 being in turn supported by the inter-connecting rod 5. These beams are also slideable upon the rod 8 for the same purpose as that of the straps 11.

Said beams 21 are shown in Figures 1 and 3 apart therefrom in Fig. 7. The sectional view of the beams shown in Fig. 8 will now be described in conjunction with the view appearing in Fig. 7.

As aforementioned the supporting beams 21 are adjustable athwart the frame so as to accommodate various sized cylinder heads upon the anchor rods 5 and 8.

In detail the beams 21 comprise a substantially channel shaped section having a pair of flanges 22, the web portion of which is extended in a loop 21a, said loop providing an adjustable attaching means for the beam upon the anchor rod 8.

The flanges 22 are cut away at 23 to form a gap, and occupying a portion of said gap is a ledge-supporting plate 25. The remaining portion of the gap formed by cutting away the flanges 22 permits the flanges 29 and 30 of the ledge, later to be described, to rest upon the supporting plate 25. The supporting plate 25, see Fig. 8, may be varied relatively in height. It is supported upon a thumb screw 26 extending through a threaded hole 24 and sustained in proper position by means of a wing nut 27.

When the cylinder head 16 rests upon the faces of the flanges 22 of the beams 21 it will be obvious that, in order that the valves in different depth compression chambers may always rest upon the valve bolsters 32; it will be necessary to have an adjustable supporting means as outlined in the preceding paragraph.

In Fig. 7 the plate 25 is shown resting upon the web portion of the beam. Such position takes care of the most shallow compression chamber. Elevating plate 25 will cause said bolsters to take care of any greater depth compression chamber.

The ledge hereinbefore referred to is detachably supported in the gap 23. It comprises a pair of angle supports 29 and 30 connected together by a splice plate 31 riveted or welded to the angle members at 28. Slidably mounted upon said angle supports are a plurality of bolsters 32 adapted for supporting the valve bodies 17. They are made of sufficient thickness to accommodate any depth compression chamber and are adjustable for

more shallow conditions by operating wing nut 26 which in turn lowers or elevates plate 25.

By referring to Figs. 4, 5 and 6 a clear conception of the different parts composing its assembly may be had. Further reference to said views discloses a reduced portion 36 of the bolster 32 which rides within the space between the angles 29 and 30. A stove bolt 34 inter-connects the bolster 32 with the angle supports 29 and 31 by means of the nut 33 and the washer 35. When the bolsters 32 are placed on the cylinders they are so arranged as to accommodate both valve bodies and keep them from falling through.

The ledge is made of sufficient length to accommodate the longest type of cylinder head so that a sufficient amount may project therebeyond as shown in Fig. 1 so that that portion may be grasped by the hands to manually rotate the cylinder to the position shown in Fig. 3. This scheme insures the valve bodies from dropping out of the cylinder head. After the cylinder head is rotated in the latter position the ledge is detached until the reconditioning work is performed after which it is again placed in its former position and the cylinder head is again manually rotated in a position for the assembling of the component parts.

Cylinder heads range in size according to the number of cylinders. They are variable in length and breadth as well as height. The present invention is universal in respect to its adaptation for the different sizes. Means to accommodate cylinder heads of various lengths and breadths have been outlined. A means for accommodating those of variable thickness will now be outlined. Such a means is shown in Figures 1 and 3, Fig. 3 illustrating more clearly why adjustment is necessary, since a correct angle for the application of tools for re-conditioning makes the job easier and simpler.

Therefore upon further observation of the latter view it will be seen the adjustment comprises a rest bar 72 to carry the inverted cylinder head. It is supported by a pair of levers 67 and 71 similar in construction except that lever 67 is provided with an adjusting stud 68. Said levers are keyed to a shaft 66 by means of a key 66a.

The adjusting stud 68 is provided with a knurled hand wheel 69 having a handle or knob 70 with which to operate the same. The end of the screw 68 rests upon the base 1 and by turning the stud will elevate or lower the rest bar 72 as described in the following operation.

After the cylinder head is swung outwardly as shown in Fig. 3 so as to rest upon bar 72, in order to adjust the level thereof, for grinding valve seats and the like, handle 70 is rotated and the stud resting on the base plates 1 elevates or lowers rest bar 72 by

levers 71 and 67. Said levers are keyed to shaft 66 at 66a, adjustment being carried back from handle 70 through crank 67 to shaft 66, it being keyed on opposite sides will 5 elevate or lower lever 71 thereby adjusting rest bar 72 which will in turn establish a correct position for re-conditioning the cylinder head.

In the re-assembly and disassembly of the 10 component parts preparatory to re-conditioning the cylinder heads I employ the use of a compressor bar of unique construction to facilitate this part of the procedure.

It is shown in operative position in Fig. 1, 15 in inoperative position in Fig. 3 and separately shown in Fig. 9 with a section thereof appearing in Fig. 10.

The compressor bar consists of a left hand bar member 37 and a right hand bar member 20 38 which are joined together by a grip 52. At the opposite end from the grip and in each of the respective bar members are holes 53 which are adapted to contain a wrist pin 53a for pivotal movement thereabout. Said 25 pin being journaled in a connecting link later to be described.

Upon the forward end of the compressor bar is mounted a stirrup 39 containing a recess for clearing the rocker arm when the 30 rocker arms are in place. In Fig. 1 is illustrated the manner of removing the pin 18 from the valve 17.

Said stirrup further comprises a pair of 35 lips 41 and 42 flanged outwardly and inwardly from the sides thereof to form a sliding guide on the bar members 37 and 38. It is adjustably joined to the compressor bar by uniting it with a U-shaped plate 43 by means of a tie bolt 44 to which is screwed a wing 40 nut 45.

As before mentioned, the use of this stirrup is limited to cylinder heads where the rocker arms remain integral with the cylinder head, and when not in use can remain 45 in the position shown in Fig. 9 without obstructing the use of the principal functioning members now to be described in conjunction with Figures 2, 9 and 10.

Valve springs as shown in Figures 1 and 50 2 are variable in diameter therefore a pair of adjustable clamping jaws 46 is essential to accommodate all conditions. They are oppositely opposed having a tapered front edge 50 extending outwardly from a downwardly projecting guide lip 51 which limits the side motion of the spring washer, while the tapered edge portions 50 bear down on the top thereof. Said jaws are held in spaced 55 relation on the top edge of the bar members 37 and 38 by inter-connecting them with a bottom strap 47 by means of a stud bolt 48 and a wing nut 49. The latter construction is clearly shown in Fig. 10.

The compressor bar is pivoted to swivelly 60 65 operate from a fulcrum link 56. The fulcrum

link is furthermore threaded and a nut 54 provides adjustment in height for the compressor bar to make it adjustable for different height cylinder heads. The lower link portion 54 is radially and slidably movable 70 upon the inter-connecting rod 5.

The illustration of the different positions of the compressor bar shown in Figures 1, 2 and 3 clearly sets forth its function in the removal of valve pins. A brief operation 75 consists of placing the cylinder head upon the frame as shown in Figure 1, over the valve support, compressor arm is rotated over valve springs, tapered jaws are made to engage valve washer as shown in Fig. 2 and finally by manually depressing the handle 52 the valve pin 18 may be easily removed.

Since certain types of automobile engines necessitate an arrangement where it is necessary to use the stirrup member, and although these are being replaced until its use 80 may be eliminated entirely, the use of this adjunct makes the device universal.

In Fig. 12 is shown an alternate supporting link 59 for the compressor bar. It differs 85 from that shown in Fig. 1 by having a ratchet adjusting 58 which is engaged by a pawl 60 screwed to the knob portion 59 thereof by means of a screw 61. A hole 65 in the knob permits partial rotation of the same. The 90 upper terminals 62 and 63 of the link containing holes 64, and the lower terminals 54a and 54b containing holes 5a are similar in construction to that shown in Fig. 1 and will not be described again. Such a modification is 95 thought to come well within the scope of the appended claims.

I claim:

1. In combination, a frame, a swingable means attachable to a valve head and pivotally mounted upon said frame to provide for moving the valve head from its normal position to an inverted position, a rest for said head, and manually operable means to adjust said rest whereby to support the valve head 10. at various inclinations in its inverted position.

2. In combination, a frame adapted to support a motor head, a two-part compressor arm adapted to pass astride the valve stems 110 of a motor head mounted upon said frame to compress the springs of the valve thereof, and a pair of cooperating jaws slidably adjustable along the two parts of said arm engageable with the springs of the motor head.

3. In combination, a frame adapted to support a motor head, a bar mounted upon said frame, said frame having side pieces adjustable toward and from each other, a compressor arm adapted to compress the valve springs of a motor head mounted upon said frame, and means slidably connecting said compressor arm with said bar.

4. In a utility device of the character described, a frame having parallel end pieces 120

sufficiently spaced apart to receive between them a motor cylinder head, a pair of anchor rods in spaced parallelism to each other connecting said end frames, beams supported by said anchor rods in parallelism with said end frames, a ledge supported by and between said beams in a vertically adjustable manner, bolsters carried by and adjustable lengthwise along said ledge, said bolsters being adapted to contact with the faces of the valves of cylinder heads to support said valves, and vertically adjustable means to support said ledge upon said beams.

5. In combination, a frame having spaced parallel end pieces adapted to swingably support a motor head, a rod interconnecting the two ends of said frame and adjustable width-wise thereof, a compressor arm adapted to compress the valve springs of a motor head mounted upon said rod, and means slidably and extendably connecting said compressor arm with said rod.

6. In combination, an adjustable frame adapted to swingably support a motor head, 25 and a two-part compressor arm including a pair of cooperating slidable jaws adapted to pass astride the valve stems of said motor head pivotally mounted upon said frame to compress the springs of the valves thereof.

30 7. In combination, a frame having spaced parallel end pieces adapted to support a motor head, said frame being provided with side pieces which are adjustable toward and from each other, a compressor arm adapted to compress the valve springs of a motor head mounted upon said frame, an adjustable rod connecting the two end pieces of said frame, and pivoted slidable means pivotally and swivelly connecting said compressor arm with 35 said rod.

8. In combination, an adjustable frame adapted to support a motor head, a two-part compressor arm including means adapted to pass astride and compress the valve springs 45 of said motor head, swivel means to which said arm is pivotally connected, pivoted means to which said swivel means is extendibly connected, whereby to facilitate the engagement of the first recited means with said springs, and a guide adapted to be adjusted toward and away from said motor head supported by said frame upon which said pivoted means is slidably mounted.

9. In combination, a frame adapted to support a motor head, swingable means attached to said motor head and pivotally mounted upon said frame whereby it may be manually swung from its normal position to an inverted position, and vice versa; means mounted upon said frame to compress the valve springs of said motor head, a ledge, beams supporting said ledge carried by said frame to support said head in its normal position, means carried by said ledge upon which said valves may individually seat after the valve

pins have been removed from the valves thereof, said ledge being adapted to be manually swung with said head.

10. In combination, a frame including end pieces adapted to support a motor head in a substantially horizontal position, a rod connecting the two ends pieces of said frame and adjustable widthwise thereof, a compressor arm adapted to compress the valve springs of a motor head slidably mounted upon said rod, and vertically extensible means connecting said compressor arm with said rod. 75

11. In combination, a frame, swingable means comprising a pair of straps attachable to a valve head and pivotally mounted upon said frame to provide for moving the valve head from its normal position to an inverted position, means comprising a pivoted cradle upon which to rest said valve head in the latter position and manually operable means to adjust said cradle whereby to vary the inclination of said valve head while inverted. 80

12. In a device of the character described, a frame including spaced parallel end pieces, a pair of adjustable anchor rods in spaced parallelism connecting said end pieces, slideable beams, one end of each of which is pivotally supported by one of said anchor rods and the other end of which is adapted to loosely rest upon the other of said rods, a ledge detachably resting on said beam and adapted to support a motor head, and means pivoted to one of said anchor rods and connectible with said motor head whereby said ledge together with said head may be manually turned bottom side up. 95

13. In a device of the character described, a frame including spaced parallel end pieces, a pair of anchor rods in spaced parallelism connecting said end pieces, slideable beams, one end of each of which is pivotally supported by one of said anchor rods; the other end of which is adapted to loosely rest upon the other of said rods, a ledge detachably resting on said beams and adapted to support a motor head, means pivoted to one of said anchor rods and connectible with said motor head whereby said ledge together with said motor head may be manually turned bottom side up, and means manually adjustable to support said motor head at various inclinations in its upturned position. 100

14. In a device of the character described, a frame including spaced parallel end pieces, a pair of adjustable anchor rods in spaced parallelism connecting said end pieces, slideable beams, one end of each of which is pivotally supported by one of said anchor rods and the other end of which is adapted to loosely rest upon the other of said rods, a ledge detachably resting on said beams and adapted to support a motor head, means to vertically adjust said ledge upon said beams, and valve supporting means carried by said ledge. 110

15. In a device of the character described, 115

a frame including spaced parallel end pieces, a pair of adjustable anchor rods in spaced parallelism connecting said end pieces, slideable beams, one end of each of which is pivotally supported by one of said anchor rods and the other end of which is adapted to loosely rest upon the other of said rods, a ledge detachably resting on said beams and adapted to support a motor head, means pivoted to one

5 10 of said anchor rods and connectible with said motor head whereby said ledge together with said motor head may be manually turned bottom side up, and a cradle manually adjustable to support said motor head at various 15 inclinations in its bottom side up position.

16. In combination, a frame structure adapted to support a motor head including side supporting pieces relatively adjustable one with the other, said side supporting pieces 20 being adapted to swingably support a motor head, a compressor arm adapted to compress the valve springs of a motor head, means carried by said arm engageable with the springs of said motor head, and a pivoted shackle-bolt 25 to which said arm is pivotally and adjustably swivelled, slidably connecting said arm with said frame structure, said pivoted shackle-bolt providing means to vary the fulcrumage of said arm whereby to facilitate 30 the engagement of the first recited means with said springs.

17. In combination, a frame structure, including side supporting pieces relatively adjustable one with the other, said side supporting pieces being adapted to swingably support a motor head, a compressor arm adapted to compress the valve springs of a motor head, means carried by said arm engageable with the springs of said head, a pivoted shackle-bolt 40 to which said arm is pivotally and adjustably swivelled, said pivoted shackle-bolt providing means to vary the fulcrumage of said arm whereby to facilitate the engagement of the first recited means with said 45 springs, and means to adjust that portion of the frame structure to which said shackle-bolt is pivoted relatively with said motor head whereby the manual pressure exerted on said arm may be varied to easify the compressing 50 of said springs.

18. In a device of the character described, a frame structure comprising a base, spaced parallel end pieces mounted upon said base, adjustable and stationary spaced parallel rods inter-connecting said end pieces, there being provided slots in said end pieces whereby the movable one of said rods is adjustable relatively to the other, beams; one end of which are pivoted to the stationary rod and the other end resting upon said adjustable rod, said beams being manually adjustable relatively with each other, straps; one end of which are pivoted to said stationary rod, the other end being adapted for attachment 60 to a swingable motor head, an auxiliary shaft 65

disposed athwart the frame, the ends of said shaft projecting beyond the end pieces of said frame structure, levers mounted on said rod, a rest bar journalled in the ends of said levers and forming in conjunction with said auxiliary shaft a pivoted cradle, and means carried by said levers whereby to adjust the position of said cradle to accommodate the swinging of said motor head. 70

19. In a device of the character described, a frame structure comprising a base, spaced parallel end pieces mounted upon said base, adjustable and stationary spaced parallel rods inter-connecting said end pieces, there being provided slots in said end pieces whereby the movable one of said rods is adjustable relatively to the other, beams; one end of which are pivoted to the stationary rod and the other end resting upon said adjustable rod, said beams being manually adjustable relatively with each other, straps; one end of which are pivoted to said stationary rod, the other end being adapted for attachment to a swingable motor head, an auxiliary shaft disposed athwart the frame, the ends of said shaft projecting beyond the end pieces of said frame structure, levers mounted on said rod, a rest bar journalled in the ends of said levers and forming in conjunction with said auxiliary shaft a pivoted cradle, means carried by said levers whereby to adjust the position of said cradle to accommodate the swinging of said motor head, a two-part compressor arm, a pivoted fulcrum link slidably mounted upon said movable rod comprising a shackle-bolt, a clevis link extendibly mounted upon said shackle-bolt to swivel thereabout, said compressor arm being pivotally mounted to said clevis link and means slidably adjustable along the two parts of said arm engageable with the springs of said motor head. 90 95 100 105

20. In combination, a frame, a bar mounted on said frame, a fulcrum link pivotally and slidably mounted on said bar, said link being composed of parts the connection of which permits rotation of one part with reference to the other about a common axis as well as longitudinal adjustment, and a compressor arm pivotally mounted to said link. 110 115
